Attorney

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM-HARNESS.

1,292,612.

Specification of Letters Patent. Patented Jan. 28, 1919.

Application filed September 15, 1917. Serial No. 191,513.

To all whom it may concern:

Be it known that I, JACOB KAUFMANN, a citizen of the United States, residing at Philadelphia, in the county of Philadelphia and State of Pennsylvania, have invented 5 certain new and useful Improvements in Loom-Harness, of which the following is a specification.

My invention relates to loom harness and 10 it has more particular relation to improved means for mounting groups of heddles in the loom harness for spaced and edge work. It is well known to those skilled in the art of weaving that the heddles which control the 15 warp ends of the selvage, particularly in ribbon weaving, are worn out much faster than the main heddles, and furthermore in various kinds of weaving it is frequently desirable to change small groups of heddles to 20 obtain slight variations in the pattern without necessitating the rearrangement of the entire body of heddles in the several frames.

The object of my invention therefore is to provide a simple and efficient heddle holder 25 adapted to support a small group of heddles, which heddle holder is so constructed and arranged as to permit the heddle holder itself to be easily changed as to its position in the harness and which also permits small 30 groups of heddles to be rearranged with a minimum of trouble at desired location as well as also to permit easy replacement of worn or broken heddles.

The nature and characteristic features of 35 my invention will be more readily understood from the following description taken in connection with the accompanying drawings forming part hereof, in which;

Figure 1 is a perspective view of a heddle 40 holder embodying the main features of my invention, the same being shown supporting a group of heddles which in turn are individually maintained in a normal vertical position by means of lingsos attached to their 45 lower ends;

Fig. 2 is a similar view showing, however, the arrangement of a pair of the heddle holders mounted in a harness frame having top and bottom bars of the usual type;

Fig. 3 is a perspective view of the heddle 50 holder detached; and

Fig. 4 is a fragmentary side elevation showing the manner of mounting the heddles in the holder.

Referring now more particularly to Fig. 1

of the drawings, 5 is a harness bar upon which the holder 6 of my present invention is mounted. This heddle holder, which is shown in enlarged perspective in Fig. 3, 60 comprises a thin flat strip of metal, the body portion 7 of which is adapted to surround the harness frame bar and is of complementary shape. Depending from each side of the main body portion 7 is a tongue 8, which is slotted as at 9, the slot of one of the tongues 65 extending open to the one edge of said tongue, and the slot of the other tongue extending to the opposite edge thereof, whereby there is thus provided central opening 10 which is closed on the one side by the bridge 70 member 11 of the one tongue and on the other side by the bridge member 11 of the other tongue. When it is desired to mount the heddles in the holder the two tongues 8 are sprung apart as in Fig. 3, and the heddles to be mounted therein are then placed with their eyes engaging the projection 12 below the slot 9, the heddles are then carried around to a position approaching the horizontal to clear the projection 12 of the 75 other tongue 8 whereupon the two tongues 8 are brought together and the heddles swung back to the normal vertical position engaging both projections 12 (see Fig. 4) thus serving to lock the holder in the closed 80 position so long as the heddles remain in the normal vertical position shown in Fig. 1, and to prevent any accidental disarrangement each of the heddles 13 may be provided 85 at its lower end with a lingo 14 of the usual 90 type.

It will be noted that the upper edges of the projections 12 are in alignment with each other, and that the opening 10 is of sufficient width whereby there will be afforded a 95 bearing surface sufficiently long to accommodate the requisite number of heddles required in each group, as well also as to permit the mounting of the heddles in the holder as above set forth (see Fig. 4). It should 100 also be noted that the holder is preferably made of spring steel or similar material so as not only to permit the placing of the device upon the harness frame bar at the desired location but also to provide a slight 105 tension upon the sides of the heddles when the same are mounted in the holder.

In Fig. 2 there is shown a pair of the heddle holders, mounted on the top and bottom bars respectively of a heddle frame of 110

the usual rectangular form, and in this instance the eyes of the heddles 13 are sufficiently long to permit sufficient play whereby after the heddles at one end are mounted 5 in the holder at that end, the heddles may be flexed or temporarily bent at the other end to be swung into engagement with the holder at that end. It will of course be understood that while this method of mounting the 10 heddles in the frame may not be practical in some instances on account of the particular dimensions of the parts, the arrangement shown in Fig. 2 may however in those cases be employed at the ends of the frame by temporarily removing the end bars of the heddle 15 frame and sliding the holders on the top and bottom bars, the group of heddles having been first mounted in the holders.

It will thus be seen that there is provided 20 a simple and efficient device for mounting small groups of heddles at desired locations in the harness which is also so constructed

and arranged as to permit the heddles to be quickly and easily mounted and dismounted for the purpose of renewal when the same 25 are worn.

Having thus described the nature and characteristic features of my invention, what I claim as new and desire to secure by Letters Patent is;

In a loom harness, a heddle holder comprising a strip of metal adapted to surround the harness frame bar and having depending tongues, each of said tongues having slots extending respectively to opposite sides 35 of said tongues to thereby provide a central opening having sufficient lateral extension to accommodate a group of heddles and providing a horizontal bearing surface for the eyes of said heddles, and said holder being 40 made of thin flat spring metal.

In testimony whereof I have hereunto signed my name.

JACOB KAUFMANN.
